UNITED STATES PATENT OFFICE

119,050

DESIGN FOR A VENDING CABINET

Samuel Rocklin, Duluth, Minn.

Application October 12, 1939, Serial No. 87,631

Term of patent 14 years

To all whom it may concern:

Be it known that I, Samuel Rocklin, a citizen of the United States and a resident of Duluth, in the county of St. Louis and State of Minnesota, have invented a new, original, and ornamental Design for a Vending Cabinet, of which the following is a specification, reference being had to the accompanying drawing, forming part thereof.

In the drawing:

I claim:

The ornamental design for a vending cabinet, as shown.

SAMUEL ROCKLIN.
